CLAIM

The ornamental design for a hinge for spectacles, as shown and described.

DESCRIPTION

FIG. 1 is a top front perspective view of the design; FIG. 2 is a top rear perspective view thereof; FIG. 3 is a front elevational view thereof; FIG. 4 is a rear elevational view thereof; FIG. 5 is a top plan view thereof; FIG. 6 is a bottom view thereof; FIG. 7 is a left side elevational view thereof; FIG. 8 is a right side elevational view thereof; FIG. 9 is a top view of the hinge of the design in a first use condition; and, FIG. 10 is a top view of the hinge of the design in a second use condition.

The broken lines in the drawings are intended to show environmental structure and form no part of the claimed design.

1 Claim, 10 Drawing Sheets
